Charles H. Dasenbrook, Rockford, Ill., assignor
to Thayer-Action Company, Rockford, Ill., a
corporation of Illinois

Application December 30, 1935, Serial No. 56,678

9 Claims. (Cl. 84—240)

This invention relates to pianos of the so-called vertical grand type in which the case is designed to present a frontal appearance similar to the conventional grand piano and the strings are disposed in vertical position so as to reduce the overall horizontal depth.

One object of the invention is to provide a vertical grand piano embodying a new and improved mechanism for transmitting the key motion to the action whip whereby to permit substantial lowering of the hammer striking line for a given length of string and therefore allow greater latitude in the design of the piano case while at the same time maintaining the necessary key level.

Another object is to provide a novel key motion transmitting mechanism for a vertical grand piano permitting the action and the keyboard to be constructed as structurally separate units and operatively connected in proper relation as an incident to assembly of the units in the piano case whereby to permit of ready removal and replacement of the key frame unit or the individual keys.

The invention also resides in the novel character of the construction which enables the key motion transmitting mechanism to be manufactured and adjusted at low cost and frictional resistance between the moving parts to be reduced to a minimum.

Other objects and advantages of the invention will become apparent from the following detailed description taken in connection with the accompanying drawings, in which

Figure 1 is a vertical cross sectional view of a vertical grand piano embodying the novel features of the present invention.

Fig. 2 is a fragmentary sectional view illustrating a modified form of key motion transmitting mechanism.

While the invention is susceptible of various modifications and alternative constructions, I have shown in the drawings and will herein describe in detail the preferred embodiment, but it is to be understood that I do not thereby intend to limit the invention to the specific forms disclosed, but intend to cover all modifications and alternative constructions falling within the spirit and scope of the invention as expressed in the appended claims.

In the drawings, the invention is embodied in a vertical grand piano comprising an elongated horizontal case having side walls 3 supporting a key bed 4, a forward wall formed in part by a fall board 5, and a removable or hinged top wall

7. The side walls are supported at their forward ends by legs 8 and at their rear ends by legs (not shown) or by a vertical housing having a front wall 9 and a sounding board 10 between which is mounted a plate 11 on which the strings 12 are stretched. By virtue of the flat top, the piano case presents a frontal appearance simulating that of an ordinary grand piano, and by arranging the strings in vertical position, the case is of narrow horizontal depth.

The key frame, which is formed as a structurally separate unit, has keys 13 fulcrumed at 14 in the usual way on a balance rail 15 supported by the bed 4 and detachably secured thereto. At its rear end, each key carries a capstan screw 16 and in the released position shown, rests against a pad 17.

The action proper is of the general design used in upright pianos and includes a metal frame bracket 18 supported at its upper end through the medium of a series of bolts 19 rigid with and projecting forwardly from the string plate 11 and at its lower end by mounting screws 20 threading into a rail 21 and mounted on lugs cast on the string plate. Pivotedly mounted on a flange 22 attached to a main rail 23 on the bracket 18 are a series of hammers 24 arranged to be projected against the respective strings 12 by depression of the corresponding keys 13. In the released position shown, the hammer shanks 25 rest against a cushion 26 on a hammer rail 27. The butt 28 of the hammer carries a leather surfaced knuckle 29 which is engaged eccentrically of the hammer pivot 30 by the end of a jack 31 pivoted at 32 on a whip 33. The latter is disposed in a generally horizontal position and is supported at its rear end from a flange on the rail 23 so as to swing about a fixed pivot 34.

As the whip 33 is swung upwardly from the idle position shown, the jack 31 is raised thereby projecting the hammer forwardly until an arm 35 on the jack strikes a regulating button 36 as the hammer approaches the string. The whip carries the usual back check 37 which coacts in a well known manner with a catcher 38 carried by the butt 28. The action also includes the usual string damper 39 on the upper end of a lever 40 which operates in a well known manner in conjunction with a spoon 41 upstanding from the rear end of the whip.

To enable the point 42 at which the hammers strike the strings to be lowered to the degree necessary for enabling a flat top to be formed on the piano case, the action unit is mounted with the whips 33 disposed substantially below 55

- the keyboard. The present invention contemplates the provision between the capstan screw 16 and the whip 33 of a novel motion transmitting connection which permits the whips to be 5 located below the keys and which is so arranged that the proper connection between each key and whip will be established automatically as an incident to assembly of the keyboard unit in the piano case.
- 10 In the preferred form shown in Fig. 1, the motion transmitting mechanism is supported from the action frame 18 and comprises a vertically extending link 43 pivotally connected at its lower end to the forward end of the whip 33 and at its 15 upper end to the rear end of a horizontally disposed lever 44 which projects over the rear end of the key 13 and is supported at its forward end to turn about a fixed pivot 45.

To enable the motion transmitting mechanism 20 to be formed and assembled as a part of the action unit, the pivot 45 is supported by a flange 46 attached to a rail 46' extending across the rear end of the keyboard and clamped by screws 47 against the vertical front face 48 on 25 the upper ends of a series of arms 49 formed as integral extensions of the action bracket 18. The screws 47 thread into the arms 49 and project through slots 50 in the rail 46' which slots allow for vertical adjustment of the rail. After 30 the rail has been located properly, fluted pins 51 snugly received in holes in the arms 49 are driven into the rail thereby locking the latter securely against displacement under the vibration encountered in service.

35 Intermediate its ends and on the underside thereof, the lever 44 carries a curved pad 52 of cloth or the like which, in the assembled positions of the action and keyboard units, bears against the rounded head 53 of the capstan screw 16. It will be seen that the upward movement of the rear end of the key lever resulting from depression of the key will swing the lever 44 upwardly and, through the medium of the link 43, this motion will be communicated to 45 the whip 33 resulting in actuation of the latter in the desired manner.

Since the operative connection between the key lever and the motion transmitting connection is at a point of abutment or bearing engagement between the capstan screw and the pad 52, this connection will be established automatically as an incident to movement of the keyboard assembly into proper position. For the same reason, the individual keys may be removed and 55 replaced if desired, and adjustment of the motion transmitting connections may be effected conveniently by turning the capstan screws, the heads of which are readily accessible while the keys are in place. Moreover, the motion transmitting parts are supported and joined together by pivotal connections of simple yet rugged character which will not settle or become displaced in normal operation of the piano. Accurate adjustment will thus be maintained 60 through long periods of service use.

By locating the point of pivotal connection between the lever 44 and the link 43 beyond the point of engagement with the capstan screw and by connecting the link to the whip forwardly 70 of the jack pivot 32 a distance sufficient to enable the link to clear the back check properly, the multiplication of the key movements necessary for effecting proper movement of the hammer is produced. It has been found that the standard key construction may be employed and the piano case

kept at the desired small depth when the parts for transmitting the key motion to the jack are proportioned approximately as shown in the drawings.

If desired, the motion transmitting mechanism may be constructed and mounted as a separate unit as shown in Fig. 2. In this embodiment, each connection includes a horizontally disposed lever 54 overlying the rear end of each key 13 and pivoted at 55 on a flange 56 fastened 10 to a rail 57 supported above the keyboard on the upstanding arm 58 of a frame 59 secured by screws 60 to the key bed 4. The forward end of the lever carries a pad 61 bearing against the head 53 of the capstan screw. The end of 15 the lever which projects rearwardly from the keyboard is pivotally connected to the upper end of a vertically extending link 62 the lower end of which is connected to the forward end of a horizontal lever 63 which is disposed below 20 the whip 33 and pivoted intermediate its ends on a flange 64 on a rail 65 secured to a downwardly projecting arm 66 of the bracket 59. The rear end of the lever 63 bears upwardly 25 against a pad 67 on the underside of the whip. 25

Since the levers 54 and 63 and their connecting link are carried by the separate frame 59 and have bearing engagement with the capstan screw and whip respectively, the action and key frame remain as structurally separate units 30 which may be assembled independently of each other. When a key is depressed, the rear end of the lever 54 is swung downwardly and its motion communicated to the lever 63 resulting in upward movement of the whip and projection of 35 the hammer against the string in the desired manner.

I claim as my invention:

1. A vertical grand piano having, in combination, a key frame having a plurality of depressible keys thereon, a substantially vertical plate disposed behind said key frame and having strings thereon one for each of said keys, a bracket opposite said key frame, hammers pivoted on said bracket to strike against the respective strings, vertically swingable whips pivoted on said bracket below the level of said keys, a rail extending across and disposed above the rear ends of said keys and supported by said bracket, levers pivoted on said rail above the rear ends of said keys, capstan screws on the rear ends of the keys bearing upwardly against the respective levers, and means connecting each of said levers to the free end of the corresponding whip including a vertically extending link 45 pivotally connected to the lever.

2. A vertical grand piano having, in combination, a key frame having a plurality of depressible keys thereon, a substantially vertical plate disposed behind said key frame and having strings thereon one for each of said keys, an action unit having a hammer and an actuating whip for each string respectively disposed above and below the level of said keys and a frame bracket, and motion transmitting connections 65 between the rear ends of said keys and the respective whips established automatically as an incident to location of said frame in operative position, each of said connections including a lever having a point of bearing engagement with 70 the rear end of one key and pivotally supported by said bracket.

3. A vertical grand piano having, in combination, a substantially vertical plate with strings thereon, an action unit having hammers for

- striking the respective strings and whips swingable about horizontal pivots to actuate said hammers and having forwardly projecting free ends, a key frame disposed forwardly from and above the level of said whips and having vertically swingable keys thereon, a rail stationarily supported above and extending across the rear ends of said keys, a plurality of horizontally disposed rearwardly projecting levers, one for each key bearing downwardly intermediate its ends against the rear end of the key and pivoted at its forward end on said rail, and a link pivotally connected at opposite ends to the rear end of said lever and the forward end of one whip respectively whereby the whip will be swung upwardly by depression of one of said keys.
4. A vertical grand piano having, in combination, a key frame having a plurality of depressible keys thereon, a substantially vertical plate disposed behind said key frame and having strings thereon one for each of said keys, a bracket, hammers pivoted on said bracket to strike against the respective springs, vertically swingable whips pivoted on said bracket below the level of said keys, a stationary rail extending across and disposed above the rear ends of said keys, a lever for each of said keys pivoted at its forward end on said rail and bearing downwardly intermediate its ends against a capstan screw on one of said keys, said lever projecting horizontally and rearwardly from the associated key, and means pivotally connected to the rear end of said lever for transmitting the movements thereof to the corresponding end of said whips.
5. A vertical grand piano having, in combination, a key frame having a plurality of depressible keys thereon, a substantially vertical plate disposed behind said key frame and having strings thereon one for each of said keys, a bracket opposite said key frame, hammers disposed above said keys and pivoted on said bracket to strike against the respective strings, vertically swingable whips pivoted on said bracket below the level of said keys, and motion transmitting connections between the rear ends of said keys and the free ends of said whips, said connections being supported by said bracket and each including a vertical link disposed behind said keys.
6. A vertical grand piano having, in combination, a substantially vertical plate with strings thereon, an action unit having hammers for striking the respective strings and whips swingable about horizontal pivots to actuate said hammers and having forwardly projecting free ends, a key bed, a key frame on said bed disposed forwardly from and above the level of said whips and having vertically swingable keys thereon, two rails extending across the rear ends of said keys and respectively supported by said bed above and below said key frame, a plurality of horizontally disposed rearwardly projecting levers pivoted intermediate their ends on said upper rail and each bearing downwardly against the rear end of the

key, a plurality of horizontally disposed rearwardly projecting levers pivoted on said lower rail and connected to the respective whips, and a vertically extending link for each key pivotally connected at opposite ends to the respective levers associated with such key.

7. A vertical grand piano having, in combination, a substantially vertical plate with strings thereon, an action unit having hammers for striking the respective strings and whips swingable about horizontal pivots to actuate said hammers and having forwardly projecting free ends, a key frame disposed forwardly from and above the level of said whips and having vertically swingable keys thereon, a rail stationarily supported above and extending across the rear ends of said keys, a plurality of horizontally disposed rearwardly projecting levers, one for each key bearing downwardly at its forward end against the rear end of the key and pivoted intermediate its ends on said rail, a vertically extending link pivotally connected at its upper end to the rear end of said lever, and a second horizontally disposed lever pivoted intermediate its ends below one of said whips and pivotally connected at one end to the lower end of said link, the other end of said second lever bearing upwardly against the free end of the whip whereby to swing the latter upwardly when the corresponding key is depressed.

8. A piano of the vertical string type having, in combination, a key unit with a plurality of depressible keys thereon, an action having a unitary rigid frame supporting a hammer and a whip for each of said keys, and connections having bearing engagement with the rear ends of the respective keys for transmitting the key motions to said whips, said connections being supported solely from said frame whereby to constitute said action and said connections a self-contained operating structure adapted to be assembled as a unit before mounting thereof in the piano case and for transmitting the motions of said keys to the respective whips and each including as an element thereof a lever having a readily disengageable connection with the rear end of one of said keys.

9. A piano of the vertical string type having, in combination, a key unit with a plurality of depressible keys thereon, an action having a unitary rigid frame supporting a hammer and a whip for each of said keys, and connections for transmitting the motions of said keys to the respective whips and each including as an element thereof a lever pivoted at one end and having a readily disengageable connection intermediate its end with the rear end of one of said keys, said connections being supported solely from said frame whereby to constitute said action and said connections a self-contained operating structure adapted to be assembled as a unit before mounting thereof in the piano case.

CHARLES H. DASENBROOK.
